OIL COOLER

Nell E. Cammack, Port Arthur, Tex.

Application July 11, 1934, Serial No. 734,699

1 Claim. (Cl. 184—104)

This invention appertains to new and useful improvements in appliances for internal combustion engines and more particularly to a novel oil cooler.

- 5 The principal object of the present invention is to provide a cooler for use in conjunction with internal combustion engines whereby oil of the crank case can be treated to maintain the same at a relatively low temperature.
- 10 Other important objects and advantages of the invention will become apparent to the reader of the following specification.

In the drawings:

15 Figure 1 is a side elevational view of the device applied to an internal combustion engine.

Figure 2 is a top plan view of the cooler attached to the engine.

20 Figure 3 is an enlarged fragmentary detailed sectional view taken substantially on line 3—3 of Figure 1.

Figure 4 is a cross sectional view taken substantially on line 4—4 of Figure 2.

25 Figure 5 is an end elevational view looking in the front end of the device.

Figure 6 is a sectional view taken substantially on line 6—6 of Figure 3.

30 Referring to the drawings wherein like numerals designate like parts, it can be seen that the numeral 5 generally refers to the internal combustion engine which is equipped with the usual crank case 6 and cooling fan 7, the fan 7 being preferably provided with an auxiliary pulley 8 used in conjunction with the present invention.

The cooler which is generally referred to by 35 numeral 9 consists of the cylindrical shell 10 provided with a header 11 in the forward end of the shell 10 and a second header at the opposite end of the shell. A plurality of tubes 13 extend through these headers and open to the atmosphere so that air can pass therethrough for cooling the oil contents of the shell.

40 A shaft 14 is journaled through the headers and on its forward end is provided with a pulley 15 which is connected to the auxiliary pulley 8 on the fan shaft by a belt 16, while inwardly of this pulley 15 is an impeller fan 17 for driving air through the tubes 13.

An outlet conduit 18 extends from the bottom of the shell 10 and connects the crank case 45 6. At the rear of the shell 10 is a pump for sucking the oil from the crank case and delivering the same to the shell 10 and this consists of the

cylindrical housing 19 into which the rear end of the shaft 14 extends through a packing gland 20. On the rear end of the shaft 14 and within the housing 19 is the rotor 21 which snugly engages the inner side of the housing. The rotor 21 is connected to the shaft 14 by a relatively thin web 22 having a pair of openings 23 and 24 therein. A plate 25 is secured against the rear side of the rotor in spaced relation with the web 22 and this is provided with a pair of struck-out portions 26, the tongues being formed by the struck-out portions being turned upwardly obliquely with respect to the plate 25.

5 An inlet pipe 27 extends from the crank case 6 and communicates with the rear end of the 15 housing 19. The forward end or header 28 of the housing 19 has a pair of pipes 30—30 extending therefrom and these communicate with the rear end portion of the shell 10.

20 It can now be seen that with the shell 10 properly supported by the straps 31—31 which in turn are suitably secured to the connecting flanges 32 between the engine crank case and engine base, the entire apparatus will be in a position for use. With the pulley 8 driving the pulley 15, the shaft 25 14 will be rotating and in operating the fan 17 will drive fresh air through the tubes 13 so as to maintain the oil passing through the shell 10 normally cool. This oil is obtained by the action of the pump blades 26 on the fluid, which cause 30 the fluid to pass from the pipe 27 through the rotor 21 by way of the pipes 30, to the shell 10.

25 While the foregoing specification sets forth the invention in specific terms, it is to be understood that numerous changes in the shape, size, and 35 materials may be resorted to without departing from the spirit and scope of the invention as claimed hereinafter.

What is claimed is:

30 In combination with a crank case, a shell having a plurality of air tubes extending therethrough, an impeller for driving air through the tubes to cool the contents of the shell, an outlet pipe from the shell to the crank case, an inlet pipe from the crank case to the shell, a fluid pump 45 in the said inlet pipe, said pump having a suction fan therein, a shaft secured at one end to the fan having an end journaled through the said shell, the opposite end of the said shaft carrying the said impeller, and drive means for the shaft. 50

NELL E. CAMMACK.
